(57) **CLAIM**

The ornamental design for a vehicle ceiling panel, as shown and described.

DESCRIPTION

FIG. 1 is an end view of a vehicle ceiling panel in accordance with a first embodiment of our new design, shown within a vehicle body, the opposite end view being a mirror image thereof;

FIG. 2 is a perspective view of the vehicle ceiling panel of FIG. 1;

FIG. 3 is a plan view of the vehicle ceiling panel of FIG. 1; FIG. 4 is an end view of a vehicle ceiling panel in accordance with a second embodiment of our new design, shown within a vehicle body, the opposite end view being a mirror image thereof;

FIG. 5 is a perspective view of the vehicle ceiling panel of FIG. 4; and,

FIG. 6 is a plan view of the vehicle ceiling panel of FIG. 4. Any parts shown in broken lines represent environment and form no part of the claimed design.
